UNITED STATES PATENT OFFICE.

JAMES E. SHAW AND JAMES T. SIMPSON, OF HOLDEN, MISSOURI.

CHURN.

SPECIFICATION forming part of Letters Patent No. 336,354, dated February 16, 1886.

Application filed June 30, 1885. Serial No. 170,258. (No model.)

To all whom it may concern:

Be it known that we, JAMES E. SHAW and JAMES T. SIMPSON, both of Holden, in the county of Johnson and State of Missouri, have 5 invented a new and Improved Churn, of which the following is a full, clear, and exact description.

Our invention relates to that class of churns wherein two concentric frames which constitute or carry the dashers are revolved in opposite directions; and the object of our invention is to provide a churn wherein the dasher-blades will alternately act to elevate and depress the cream, so that in the end the top of 15 the cream will be on a general level; and a further object of our invention is to construct an inner dasher which, when revolved in one direction, will throw the cream to the blades of the outer dasher, but which, when the direction 20 of rotation is reversed, will act to throw the cream or gather the butter in the center of the churn.

The invention consists of certain details of construction and combinations of parts, as will 25 be hereinafter described, and pointed out in the claims.

Reference is to be had to the accompanying drawings, forming part of this specification, in which similar letters of reference indicate 30 corresponding parts in all the figures.

Figure 1 is a side elevation of our improved churn, a portion of the barrel being removed to disclose the construction of the dashers. Fig. 35 2 is a central vertical section of the churn, taken on line *x* *x*, Fig. 1; and Fig. 3 is a sectional view taken on line *y* *y*, Fig. 1.

A represents the body or barrel, and *B* the cover, of the churn. This cover *B* is made in two sections, *o* *o*', the section *o*' being so arranged 40 that it can easily be removed for the purpose of pouring in and inspecting the cream. A frame or stand, *C*, arranged to support the dasher-operating mechanism, is securely fastened to the section *o* of the cover *B*. This operating or driving mechanism consists of two beveled gears, *E* and *F*, that are keyed to a shaft, *a*, that is mounted in bearings formed in the frame *C*. The gear *F* engages with a beveled pinion, *b*, that is fixed to the shaft *c* 45 of the inner dasher, *H*, the lower end of the shaft *c* being mounted in a step, *e*, that is fixed to the bottom of the churn-body *A*, while the

upper end passes through and is guided by the brace-rod *f* of the frame *C*. The gear *E* meshes with the beveled pinion *h*, that is fixed to the cylindrical shaft *g* of the outer dasher, *I*, said shaft *g* inclosing the shaft *c*, as shown in Fig. 2. Such being the construction of the driving mechanism, it will be clearly seen that if the gear-wheel *E*, which is provided with a handle, be revolved in the direction of the arrow the dasher-shafts will be revolved in the direction of the arrows shown around them.

We are aware that such a construction for operating the dashers as is above described 65 has heretofore been used, and we therefore do not claim these features *per se*; but we are not aware that churn-dashers have been heretofore constructed in the form and manner now to be specifically explained.

The outer dasher consists of two substantially-concentric strips, *k* and *l*, which are rigidly connected to the lower end of the cylindrical shaft *g*, and guided below by the shaft *c*, which passes through them to rest within the step *e*. Between the strips *k* and *l* we secure several 75 pairs of dasher blades or buckets, as *i* *i*'. These blades or buckets are put in pairs in about the same horizontal plane, one blade in each pair being on either side of the shaft, but both blades 80 in the same pair being in the same diagonal plane. Every other pair of blades *i* *i*' is put in at about the same angle, and the intervening pairs are put in at an opposite angle, so that taking the dasher circumferentially every 85 second blade will have a tendency to elevate the cream and the other blades will have a tendency to depress it. The blades that act to elevate the cream when the dasher is revolved in the direction of the arrow are marked 90 *i*', and those that tend to depress it are marked *i*. The vertical blades or buckets *n* *n*' are also placed between the strips *k* *l*, one of which, *n*, acts to throw the cream outward, while the other, *n*', acts to cause an inward current.

The inner dasher is composed of a series of flat blades, *m* *m*, of which there are preferably four that are rigidly secured to the inner revolving shaft, *c*. These blades are so twisted that the sides which would be in advance when the dasher is revolved in the direction of the arrow *g* are bent inward, so that instead of presenting a sharp edge that would simply cut through the cream the blades pre-

sent a tangential surface, which strikes the cream and creates a current toward the outer dasher.

As before stated, the dasher-blades *i i'* are arranged in pairs, each pair being in substantially the same vertical plane, but on opposite sides of the dasher, so that each pair are in the same diagonal plane, and will act to alternately create an upward and a downward current.

In operation our churn is at first started in the direction of the arrows and the rotation of the dasher-frames continued until the cream has separated, the action of the inner dasher at this time being to induce a current toward the outer dasher-blades; but when the butter has formed the direction of rotation is reversed, and the inner dasher will then act to gather the butter in the center of the churn.

Having thus described our invention, we claim as new and desire to secure by Letters Patent—

1. The combination, with a churn and its operating mechanism, of an outer dasher-frame carrying fixed dasher-blades arranged in pairs, one blade of each pair being mounted on either

side of the central shaft, and both blades being mounted in substantially the same diagonal plane, substantially as set forth.

2. The combination, with a churn and its operating mechanism, of an outer dasher-frame carrying dasher-blades arranged in pairs, one blade of each pair being mounted on either side of the central shaft, and both blades being mounted in substantially the same diagonal plane, and an inner series of dasher-blades, the forward edges of said blades being bent inward toward the central shaft, substantially as described.

3. The combination, with a churn and its operating mechanism, of two dasher-frames, as H and I, said frame I being provided with diagonally-mounted dasher-blades, as *i i'*, and said frame H being composed of blades, as *m m*, bent so that their leading edge will approach the central shaft, substantially as described.
